(57) **CLAIM**

The ornamental design for a display panel with news labels graphical user interface, as shown and described.

DESCRIPTION

FIG. 1 is a front view of a display panel with news labels graphical user interface, according to a first embodiment. FIG. 2 is a front view of a display panel with news labels graphical user interface, according to a second embodiment. FIG. 3 is a front view of a display panel with news labels graphical user interface, according to a third embodiment. FIG. 4 is a front view of a display panel with news labels graphical user interface, according to a fourth embodiment. FIG. 5 is a front view of a display panel with news labels graphical user interface, according to a fifth embodiment. FIG. 6 is a front view of a display panel with news labels graphical user interface, according to a sixth embodiment. FIG. 7 is a front view of a display panel with news labels graphical user interface, according to a seventh embodiment. FIG. 8 is a front view of a display panel with news labels graphical user interface, according to an eighth embodiment. FIG. 9 is a front view of a display panel with news labels graphical user interface, according to a ninth embodiment. FIG. 10 is a front view of a display panel with news labels graphical user interface, according to a tenth embodiment. FIG. 11 is a front view of a display panel with news labels graphical user interface, according to an eleventh embodiment.

FIG. 12 is a front view of a display panel with news labels graphical user interface, according to a twelfth embodiment. FIG. 13 is a front view of a display panel with news labels graphical user interface, according to a thirteenth embodiment.

FIG. 14 is a front view of a display panel with news labels graphical user interface, according to a fourteenth embodiment.

FIG. 15 is a front view of a display panel with news labels graphical user interface, according to a fifteenth embodiment.

FIG. 16 is a front view of a display panel with news labels graphical user interface, according to a sixteenth embodiment.

FIG. 17 is a front view of a display panel with news labels graphical user interface, according to a seventeenth embodiment.

(Continued)

FIG. 18 is a front view of a display panel with news labels graphical user interface, according to an eighteenth embodiment.

FIG. 19 is a front view of a display panel with news labels graphical user interface, according to a nineteenth embodiment.

FIG. 20 is a front view of a display panel with news labels graphical user interface, according to a twentieth embodiment; and,

FIG. 21 is a front view of a display panel with news labels graphical user interface, according to a twenty-first embodiment.

The outermost broken lines in the drawings illustrate an electronic device and are included for the purpose of illustrating the environment of the design and form no part of the claimed design. The remaining broken lines illustrate portions of the graphical user interface that form no part of the claimed design.
